UNITED STATES PATENT OFFICE.

JAMES F. EPPENSTEIN, OF ELGIN, ILLINOIS, ASSIGNOR TO ILLINOIS WATCH CASE COMPANY, OF ELGIN, ILLINOIS, A CORPORATION OF ILLINOIS.

DESIGN FOR A VANITY CASE.

Application filed January 18, 1926. Serial No. 16,153. Term of patent 3½ years.

To all whom it may concern:

Be it known that I, JAMES F. EPPENSTEIN, a citizen of the United States, residing at Elgin, in the county of Kane and State of Illinois, have invented a certain new, original, and ornamental Design for Vanity Cases, of which the following is a specification, reference being had to the accompanying drawing, forming part hereof, wherein is illustrated a perspective view of a vanity case showing my new design.

I claim:

The ornamental design for a vanity case as shown.

JAMES F. EPPENSTEIN.
